UNITED STATES PATENT OFFICE.

NORMAN B. HURD, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

DOOR HOLDER.

Application filed September 16, 1926. Serial No. 135,781.

My invention relates to a door holder for holding a door in predetermined open position.

It is an object of the invention to provide 5 an improved door holder which will be simple in construction and effective in use for holding a door in predetermined open position.

It is a further object to improve certain 10 details of construction in a door holder of the character indicated.

Briefly stated, in the preferred form of 15 the invention I employ a pair of arms, one to be secured to a door and the other to be secured to a door casing. These arms are 20 pivotally connected to each other at their outer ends. One of the arms at one side may have one or more cam surfaces, and one or more wedging members are provided for coaction with the cam surfaces on said arm. Means may be provided for adjusting the 25 limit of swinging movement of said arms and consequently determining the position at which a door is held.

25 In the drawings which show, for illustrative purposes only, a preferred form of the invention—

Fig. 1 is a top plan view of a door holder embodying features of the invention and applied to a door and door casing;

Fig. 2 is an enlarged fragmentary, sectional view through the pivot end of the door holder shown in Fig. 1;

Fig. 3 is a perspective view of parts shown 35 in Fig. 2, various elements being separated to facilitate illustration.

In said drawing, 5 indicates a door casing while 6 indicates a usual door. My improved door holder includes an arm 7 which 40 may be pivotally secured to the door casing 5, and a second arm 8, which may be pivotally secured to the door 6 or to a door closer 9 carried thereby. The arms 7—8 are pivotally connected to each other by means 45 of a pin or bolt 10.

In the preferred form shown, the arm 8 is provided with an angular aperture or bore 11, and the pin 10 is provided with an angular portion 12 fitting the bore 11 and thus 50 non-rotatably holding the pin 10 in the arm 8. The arm 7 is provided with a circular bore 13 adapted to fit the correspondingly shaped portion 14 on the pin 10. The two arms 7—8 are thus pivotally connected together. If desired, the arms 7—8 may have

abutting plane bearing surfaces coating with each other and, in the form shown, I interpose a thin washer or wear disk 15 between these bearing surfaces.

The outer side of the arm 7 may have one 60 or more arcuate cam surfaces 16—17 and, in the preferred form shown, these cam surfaces are oppositely inclined. Wedging means 65 cooperate with the cam surfaces 16—17, and in the form shown, I employ wedges or friction shoes 18—19, which may be supported or carried by a cross member or pin 20, which may itself be carried by and transversely of the upper end of the pin 10. The cross pin 20 may loosely fit 70 the transverse aperture in the pin 10, and wedges 18—19 are loosely held or supported over the corresponding cam surfaces 16—17 respectively as shown particularly in Figs. 2 and 3. If desired, a suitable cover member 75 21 may be provided for housing the cam surfaces and wedging members and providing a structure of finished appearance. The lower end of the pivot pin 10 may be threaded and an adjusting nut 22 provided 80 thereon for varying the limit of the swinging movement of the arms 7—8, as will be described.

The operation of the device is as follows: 85 When the parts are assembled, as shown, for example in Fig. 1, and the door is opened, the arms 7—8 will swing relatively to each other. When the nut 22 is turned up to the desired position, the relative swinging movement between the arms 7—8 will be 90 limited by the wedging members 18—19 riding up on their respective cam surfaces 16—17. By backing off on the nut 22, a more extensive swinging between the arms 7—8 is permitted and, conversely, by turning up on the nut 22, the extent of swinging 95 between the arms 7—8 will be decreased. By reason of the fact that the pivot pin 10 always turns with the arm 8, there is no substantial tendency of the nut 22 to work 100 loose after a repeated opening and closing of the door. In the particular form shown, wherein the arms 7—8 bear on each other through the wear washer or plate 15, the wedging means, above described, serves principally to force the two arms toward each other and the frictional force between the surfaces on the arms and the wear plate 15 hold the door in desired position, but, of course, the friction between the wedging

means and corresponding cam surfaces contributes to this holding action.

By reason of the very large area of contact between the arms 7-8 around the pivot 10, and whether or not a wear washer 15 is employed, it requires but comparatively little pressure to cause the parts to frictionally jam sufficiently to hold the door in predetermined open position. Thus, the wear on the wedge shoes 18-19 is slight and slow. Furthermore, by placing the wedge shoes on opposite sides of the pin 10 it tends to balance the strain, and even though one shoe is shown as somewhat farther from the axis 15 of the pin 10 than the other shoe, this arrangement tends to equalize or balance the pressure so that the bearing head on the end of the arm 7 will slide more freely on the pin 10 than were the pressure applied wholly on one side of the pin. For this reason, it is preferred that there should be two wedge shoes employed.

It is to be noted that this door holder may be used with equal facility on both right and left hand opening doors, and without reversal or change of parts.

In a door holder, as above described, there is little likelihood that the parts will get out of order or fail to function, and the parts are all relatively cheap and simple to manufacture. The wedging means or shoes 18-19 are very simple and cheap in construction and should they become worn they may be easily replaced at small cost. The same is true of the wear plate 15 interposed between the two arms.

While the invention has been described in some detail, I do not wish to be strictly limited to the particular form and construction shown since changes may be made within the scope of the invention as defined within the appended claims.

I claim:

1. In a door holder, a pair of arms pivotally connected to each other, one of said arms having two arcuate cam surfaces on one side thereof, and wedging means coacting with said cam surfaces for limiting the swinging movement of said arms.
2. In a door holder, a pair of arms pivotally connected to each other, one of said arms having a plurality of arcuate cam faces thereon, and wedging means coacting with said cam surfaces for limiting the swinging movement of said arms.
3. In a door holder, a pair of arms, a pivot pin for connecting said arms, one of said

arms having a plurality of arcuate cam surfaces thereon, and means carried by said pivot pin and coacting with said cam surfaces for limiting the swinging movement of said arms.

4. In a door holder, a pair of arms pivotally connected to each other, one of said arms having a plurality of cam surfaces on one side thereof and located at different distances from the axis thereof, said cam surfaces being oppositely inclined, and wedging means coacting with said cam surfaces for limiting the swinging movement of said arms.

5. In a door holder, a pair of arms, a pin non-rotatably carried by one of said arms and pivotally connecting said arms together, a plurality of wedging means carried by said pin, one of said arms having a plurality of cam surfaces for coaction with said wedging means for limiting the swinging movement of said arms.

6. In a door holder, a pair of arms, a pivot pin non-rotatably carried by one arm and serving to pivotally connect said arms, a cross pin carried by said pivot pin, wedging means carried by said cross pin, one of said arms having a cam surface for engagement with said wedging means for limiting the swinging movement of said arms.

7. In a door holder, a pair of arms, a pivot pin non-rotatably carried by one arm and serving to pivotally connect said arms, a cross pin carried by said pivot pin, a plurality of wedging means carried by said cross pin, one of said arms having a plurality of cam surfaces for engagement with said wedging means for limiting the swinging movement of said arms.

8. In a door holder, an arm having an angular bore therethrough, a pivot pin having an angular portion fitting said angular bore so as to hold said pivot pin to said arm non-rotatably, a second arm rotatably carried on said pin, a cross member carried by said pivot pin adjacent the end opposite said angular portion, a pair of wedging members carried by said cross member on opposite sides of said pin, the side of said arm adjacent said wedging means having a pair of cam surfaces inclined oppositely to each other for coaction with said wedging means for limiting the swinging movement of said arms, and a nut carried by said pivot pin for varying the limit of swinging movement of said arms.

NORMAN B. HURD.
